UNITED STATES PATENT OFFICE.

WESLEY M. WAY, OF AUSTIN, TEXAS, ASSIGNOR TO GEORGE W. TROMMLITZ, OF GALVESTON, TEXAS.

WIRELESS-TELEGRAPH RECEIVER.

No. 918,618.

Specification of Letters Patent. Patented April 20, 1909.

Application filed March 7, 1908. Serial No. 419,780.

To all whom it may concern:

Be it known that I, WESLEY M. WAY, a citizen of the United States, residing at Austin, in the county of Travis and State of Texas, have invented a new and useful Wireless-Telegraph Receiver, of which the following is a specification.

This invention has reference to improvements in wireless telegraph receivers, that is, means for receiving intelligence communicated by electric waves, and is designed more particularly for using silicon or other crystalline substance as the detector element.

The present invention comprises a holder for a lump of the rough crystalline substance together with means for adjusting a movable circuit terminal in the proper relation to the crystalline substance when seated in the holder, and provision is made for all the adjustments found necessary.

More specifically considered, the invention comprises a cup or holder for a crystal or a mass of crystals for the substance used capable of rotating on a vertical axis, and in conjunction with this holder there is a carriage also capable of rotative movement upon a vertical axis. The carriage supports a bar mounted upon trunnions so as to move about a horizontal axis, and this bar is provided with opposing springs so that it may be adjusted accurately as to the pressure desired, and carried by the bar is a terminal screw which may be brought into contact with the crystal or mass of crystals in the holder. The carriage and the parts supported thereby are connected up on one side of the circuit of the aerial and the holder for the crystal is connected up on the other side so that the ether or Hertzian waves must pass through the crystal. The detector may be coupled up to the aerial and receiver circuit in the usual manner.

The invention will be best understood from a consideration of the following detail description taken in connection with the accompanying drawings forming part of this specification, in which drawings,—

Figure 1 is a side elevation of the detector. Fig. 2 is a plan view with parts broken away and the circuits shown diagrammatically. Fig. 3 is a detail section through the holder for the crystal, and Fig. 4 is an elevation of the carriage with the bar in section and the crystal holder removed.

Referring to the drawings, there is shown a base 1 which may be of any suitable material, and it is to be considered indicative of any suitable support since the parts mounted upon the base may be otherwise mounted. This base is of course of suitable insulating material. Fast upon the base near one end thereof is a plate 2 secured to the base by screws 3 or in any other suitable manner. Rising from the middle of the base is a post 4 which may be suitably screw threaded for the reception of a clamp nut 5.

Mounted upon the base 2 is a yoke-shaped carriage 6 suitably perforated for the passage of the post 4, and this carriage is held to the plate 2 by means of the clamp nut 5, the post 4 passing through the carriage at a point midway of its length. The carriage may consist of a single metallic strip having its ends bent at approximately right angles to the middle portion and extending upward with the ends 7 parallel one to the other but spaced apart an appropriate distance. Each leg end 7 is appropriately tapped for the passage of a pivot screw or thumb screw 8, to which latter there is applied a clamp nut 9. The ends of the screws 8 are socketed for the reception of the pointed trunnions 10 either formed on a bar 11 or made of a rod pointed at each end and extending laterally through the bar 11. Both the bar 11 and the trunnions 10 may be similar in construction to the ordinary key lever of the telegraph transmitter of the commercial type. This bar 11 has a short extension 12 on one side of the trunnions and the long member on the other side of the trunnions. About midway of the length of the long end the bar 11 is tapped for the passage of a thumb screw 13, and this thumb screw carries a clamp nut 14. The free end of the thumb screw has secured thereto a hook 15 receiving one end of a helical spring 16, the other end of which engages a hook 17 fast on the corresponding side of the carriage 6 adjacent to the clamp nut 5. On the other side of the carriage from the hook 17 is another hook 18 receiving one end of a helical spring 19, the other end of which is fast on a hook 20 secured to the end 12 of the arm 11. The end 12 of the bar 11 remote from the extension 10 is tapped for the passage of a long thumb screw 21 carrying a clamp nut 22.

Fast upon the base 1 at the end thereof remote from the plate 2, there is secured a cylindrical block 23 by means of a screw 24 or in any other manner. On top of this block

5 is a plate 25 secured thereto by an overhanging flange 26 of the screw sleeve 27 adapted to thread on the block 23. Formed on the plate 25 at its center is a boss 27 from which rises a number of outwardly-extending arms 10 28 so grouped as to constitute a cup or holder for a mass 29 of suitable material such as a crystal or a group of crystals, and preferably a rough crystal or group of crystals of silicon, since the last-named substance is 15 found to give most excellent results. The location of the screw 21 and of the cup formed of the arms 28 is such that when a mass 29 is seated in the cup the free end of the screw 21 will make contact therewith.

20 Mounted upon the base 1 are two binding posts 30-31. The binding post 30 is connected by a conductor 32 to the plate 2, which like the other parts of the structure aside from the base and the crystalline mass 25 29 is made of metal, and the binding post 31 is connected by a conductor 33 to the block 23. Of course the connections of the binding posts may be reversed. The circuit terminals of the receiving aerial are indicated at 34.

By using the rough crystalline mass 29 seated in the cup 28 and held therein by the screw 21, the adjustment of the crystalline mass is insured, since shocks and jars will 35 not interfere with an adjustment once made, and a serious difficulty heretofore present in detectors of this character is avoided. Furthermore the cup or holder, because of the fingers 28, is readily shaped to the crystal 40 and because of its capability of rotation on the block 23 may be turned upon a vertical axis to adjust the crystal to the screw 21. It is found that the rough crystalline pieces give better results than pieces that have 45 been ground down smooth.

The carriage 6, because of its capability of rotative movement upon the pin or stud 4 may be moved about said pin or stud as an 50 axis to bring the end of the screw 21 into proper relation to the crystal 29. By adjusting the pivot screws 8 so that the bar 11 is free to move about its screws as an axis, the bar 11 automatically adjusts itself to the crystal. If the screws 8 be made tight 55 then the adjustments are made through the screw 21. The two opposing springs 16 and 19 are adjustable through the screw 13 and when once adjusted counteract jars and knocks, and thus the adjustment between the 60 screw 21 and the crystalline block or mass 21 is maintained automatically under the various conditions of use.

The cup or holder and the carriage have 5 been described as rotatable about vertical axes but this statement is to be taken in a

relative sense only, since they may rotate on axes set at any angle to the vertical, although usually the instrument will be used upon a horizontal surface so that the axis of the cup and holder are really substantially 70 vertical.

What is claimed is:—

1. An electric wave detector comprising a cup or holder for a suitable crystalline mass, said cup being rotatable, a carriage movable 75 about an axis parallel to the axis of rotation of the cup or holder, an arm pivotally connected to the carriage and movable about an axis at right angles to the axis of rotation of the carriage an adjustable contact screw 80 carried by the arm in position to engage a crystalline mass carried by the holder, and opposing springs connected to the carriage and to the arm on opposite sides of the pivot 85 of the latter.

2. An electric wave detector comprising a holder for a crystal or mass of crystals, and a universally mounted terminal arranged to engage the crystalline mass, said terminal comprising a rotatable support, an arm pivoted on said support for movement at right angles to the axis of the support, means on 90 said arm for engaging the crystalline mass when in the holder, and means for clamping the support in any adjusted position of rotation about its axis. 95

3. In an electric wave detector, electric circuit terminals arranged to grasp a crystal or crystalline mass between them, one of said terminals being provided with a cup or 100 holder for the crystalline mass and rotatable about a central longitudinal axis, and the other terminal being rotatable about an axis spaced from the axis of the first named terminal and parallel therewith.

4. An electric wave detector comprising a support or carriage having a movement of rotation about a suitable pintle, clamping means for holding the carriage in adjusted positions, an arm pivotally connected to the 110 carriage for movement at right angles to the movement of rotation of the carriage, clamping means for locking the arm in any adjusted position, springs engaging the arm on opposite sides of its pivot and acting in opposition, means for adjusting one of the 115 springs, an adjustable circuit terminal carried by the arm and having means for locking it in adjusted position, a cup or holder for a crystal or crystalline mass in line with the circuit terminal on the arm, and rotatable on an axis longitudinal to the adjustable circuit terminal carried on the arm, and means for carrying the cup or holder in adjusted positions.

5. In an electric wave detector, a rotatable cup or holder rotatable about its central longitudinal axis and adapted to hold a crystal or crystalline mass, said cup or holder constituting a circuit terminal, and another 125 130

circuit terminal yieldingly engaging such crystalline mass when in the cup and mounted for adjustment on an axis spaced from but parallel to the axis of rotation of the cup or holder.

6. In an electric wave detector, a rotatable cup or holder rotatable about its central longitudinal axis and adapted to hold a crystal or crystalline mass, said cup or holder constituting a circuit terminal, means for clamping the cup or holder in any adjusted position of rotation, and a circuit terminal

yieldingly engaging such crystalline mass when in the cup and mounted for adjustment on an axis spaced from but parallel to the axis of rotation of the cup or holder.

In testimony that I claim the foregoing as my own, I have hereto affixed my signature in the presence of two witnesses.

WESLEY M. WAY.
